SHEET FEEDING APPARATUS

Hans L. Kabel, Modesto, Calif., assignor to The Borden Company, New York, N. Y., a corporation of New Jersey

Application April 29, 1941, Serial No. 390,883

2 Claims. (Cl. 271—32)

This invention relates to apparatus for feeding sheet material.

In the operation of metal working machines handling sheet material, it is usually desirable to supply the sheets rapidly and one at a time. For example, sheets of tinplate have to be fed rapidly and uniformly to can body or similar machines in order to have these machines operate efficiently. For this purpose, the sheets of material are frequently arranged in a vertical stack and a feeding arrangement is provided for withdrawing one sheet at a time from this stack and feeding it to the machine that forms it into a can or performs other operations upon it.

In magazine feeding devices of this type, however, it is very important to avoid the feeding of more than one sheet at a time. When two or more sheets stick together and are fed to the forming or operating machine, jamming of the machine is apt to occur, requiring stoppage of the entire machine. If the forming machine is not actually damaged, there is at least a substantial waste of sheet material. It is particularly difficult to prevent two or more sheets of flat sheet material from sticking together in a vertical magazine due to the smooth surfaces of the sheets and the weight of sheets in the magazine. This problem is further increased by the development of higher feeding speeds requiring in some cases the accurate and efficient feeding of sheets from a magazine at the rate of several hundred a minute.

One object of my invention is to provide apparatus for feeding sheet material from a magazine so that no more than one sheet is taken from the magazine at a time and so that the sheet selected is not nicked or otherwise damaged during the feeding operation.

Another object of the invention is to provide magazine feeding apparatus for sheet metal which is readily adjustable for different sizes of sheets and which is sufficiently flexible to feed only one sheet at a time even though the sheets vary slightly from each other in size.

Other objects will be apparent from a description of the preferred embodiment of my invention in the accompanying drawings, in which

Figure 1 is a vertical sectional view through approximately the center of a magazine feeding device for sheet metal.

Figure 2 is a vertical sectional view through the apparatus, taken on the offset line 2—2 of Fig. 1.

Figures 3 and 4 are vertical sectional views similar to the upper portion of Fig. 2, showing the

apparatus in different positions during the feeding operation.

Figure 5 is a sectional view, taken on the line 5—5 of Fig. 1.

Figure 6 is a perspective view of one of the stripper members.

Figure 7 is a sectional view, taken on the line 7—7 of Fig. 6.

The embodiment of the invention illustrated in the drawings may be used for feeding sheets to any suitable machine such as the feeding of sheet tinplate into a can body machine, into a cutter for cutting the sheets to sizes, or into machines for performing various other operations upon the sheet material. The actual forming or operating machine is not illustrated in the drawings since it forms no part of my invention.

Numerical 10 indicates the vertical guide columns, of which there may be four, forming a magazine to hold a stack of sheets 11. The guide columns 10 may be either fixed in position or adjustable to accommodate sheets of different sizes, as will be understood by those skilled in the art.

20 A ledge 10a may be provided extending between two of the guide columns 10 to support one side of the stack of sheets, and brackets 10b having rounded ends may be fixed to the other two of the columns 10 to support the other two corners of the stack of sheets 11. The ledge 10a and brackets 10b thus support the weight of the stack.

Immediately below the stack of sheets 11 are a pair of vertically reciprocating suction cups 12 supported at the upper ends of rods 13 which in turn are fixed to the block 14. These vacuum cups 12 may be connected by the flexible hose 12a to a vacuum pump with a suitable timing mechanism (not shown) for alternately applying and relieving the vacuum, as is customary with feeding devices of this type. The block 14 may be carried by the slide 15 adapted to slide up and down between the inclined guides 16. Movement may be imparted to the block 14 by means of a link 17 having its upper end pivotally connected to the block 14 by means of the pin 18. The lower end of the link 17 is pivotally connected by the pin 19 to one side of the flywheel 20 that rotates with the shaft 21. Any suitable means (not shown) may be employed for rotating shaft 21.

A horizontal slide 22 having an enlarged end 22a is supported for reciprocation on the table 23 and is moved back and forth by the link 24 pivotally connected at one end by means of the

pin 25 to the depending lug 26 fixed to the bottom of the slide 22. The other end of the link 24 is pivotally connected by means of a pin 27 to the rocker arm 28, which is rocked back and forth about the shaft 29 by any suitable means (not shown).

At the other side of the magazine opposite the slide 22, a pair of positively driven rolls 30 are disposed for feeding sheets pulled from the magazine onto the continuous belt conveyor 31, which carries these sheets one at a time in properly spaced relation into a can body, or other type of forming machine.

Each pair of guide columns 10 is connected together by a bar 32 held in place by bolts or other suitable means. One or more brackets 33 may be clamped or otherwise secured on each of the bars 32 with their legs 34 and 35 straddling the bars 32. These brackets 33 may be clamped securely to the bars 32 in any desired position by means of the bolts 36 acting as set screws. The legs 35 of the brackets 33 extend up to form the upwardly extending arms 37, and stripper members 38 are attached to and resiliently supported by these arms 37.

The stripper members 38 preferably comprise pairs of inwardly and downwardly inclined fingers 39, the lower inner surfaces of which are serrated, as indicated at 40. The fingers 39 of each stripper member 38 may be integral with and connected together at their top by straps 41 provided with suitable openings 42. The stripper members 38 may be mounted on the arms 37 of the brackets 33 by means of bolts 43 extending through openings in the arms 37, the openings 42, and coil springs 44 held in place by means of the nuts 45.

It will be apparent that by loosening the bolts 36, these stripper members 38 may be mounted in a vertical position or inclined in either direction at will, or moved to any suitable locations on the bars 32. The coil springs 44 serve to provide a resilient mounting for the stripper members 38 permitting them to be pressed laterally outward from the magazine, or permitting tilting of them in any direction against the compression of the springs 44. The resistance of these springs 44 may be readily varied by tightening or loosening the nuts 45.

The serrations 40 on the inclined surfaces of the stripper fingers 39 preferably are rounded somewhat, as illustrated, to avoid nicking or otherwise damaging the edges of the sheets pulled down over them. Also, these serrations are preferably formed so that less resistance is offered to upward movement of the sheets than to downward movement thereof.

In the operation of this feeding device, a stack of sheets 11, for example, rectangular sheets of thin tinplate suitable for use in making can bodies, is placed in the magazine between the guide columns 10 with the lowest sheet of this stack resting on the shelf 10a and the pair of corner brackets 10b. Rotation of the shaft 21 and flywheel 20 causes the link 17 to reciprocate, moving the slide 15, block 14, rods 13 and vacuum cups 12 up and down in the direction of the inclined guides 16.

As the vacuum cups 12 reach the top of this stroke, suitable timing mechanism (not shown) supplies vacuum through the flexible hose 12a to the vacuum cups 12, which are thus fastened to the central portion of the lowermost sheet in the stack 11. As the vacuum cups 12 are pulled downwardly, the corners of the lowermost sheet, and usually of two or three sheets thereabove,

are flexed and pulled out of engagement with the shelf 10a and corner brackets 10b. The side edges of these sheets are then held simply by the inclined surfaces of the stripper fingers 39.

Because of the smooth surfaces of these sheets and the pressure holding them together in the magazine, it requires a considerable force to pull them apart unless the suction between the individual sheets is first broken. The vacuum cups 12 travel downwardly, however, at an inclined and there is a certain amount of slippage between the sheet fastened to the vacuum cups and those immediately above it, which assists in breaking this suction between the sheets. Also, as soon as the sheet to be fed and those that have been pulled free of the magazine supports strike the stripper fingers 39, the inwardly and downwardly inclined surfaces of the stripper fingers cause the sheets to flex and the serrations 40 catch the edges of the sheets that have been pulled from the bottom of the stack. By the time that the lowermost sheet has been pulled clear of the stripper fingers 39, therefore, it has been positively separated from the next sheet above it and only one sheet 25 is carried down through the rest of the downward stroke of the vacuum cups 12.

By reason of the inclined movement of the vacuum cups and their support, one edge of the sheet attached thereto is brought to a position 30 where it is just touching the revolving rolls 30. And by this stage in the operation, the vacuum in the cups 12 has been broken by the timing mechanism previously referred to.

The slide 22 by this time has been moved a short distance towards the rolls 30 by the link 24 and rocker 28. The front end 22a of this slide 22 strikes one edge of the sheet that has been pulled down by the vacuum cups 12, thus forcing the opposite edge of the sheet between the rolls 40 30 which pick it up and quickly transfer it to the continuous belt conveyor 31.

While this sheet is being transferred to the conveyor 31 by the rolls 30, the vacuum cups 12 complete their downward stroke to a point substantially below the level of the slide 22, so that as soon as the sheet is removed by rolls 30, the vacuum cups 12 are moving upwards again toward the bottom of the stack 11. When the vacuum cups 12 again reach the bottom of the stack 11, they fasten onto the lowermost sheet and repeat the operation. The angle of the teeth or serrations 40 on the stripper fingers 39 is such that a sheet supported between them may be easily pushed up against the bottom of the stack 55 11 by the vacuum cups 12 before they start their downward stroke.

A particular advantage of the resiliently supported stripper fingers 39 in preventing the feeding of more than one sheet at a time, is that 60 these stripper fingers may be tilted or inclined at different angles to the vertical by simply loosening the bolts 36 and adjusting the positions of the brackets 33 on the bars 32. It has been found desirable to have the serrations 40 on the stripper finger surfaces somewhat rounded at the corners and inclined to permit any sheets that are pulled down below the bottom of the stack to be easily pushed upwards again by the vacuum cups 12. This avoids nicking or otherwise damaging the edges of the sheets.

While the stripper fingers 39 have been illustrated in the drawing in a position inclined to the vertical, the inclination being similar to the angle of inclination of the stroke of vacuum cups 75 12, it is to be understood that the vacuum cups

12 may be moved through a plain vertical path or pulled downwardly at another angle than the one shown, and the stripper fingers may be correspondingly adjusted. Furthermore, it is not necessary to have the stripper fingers inclined at the same angle as the angle of movement of the vacuum cups 12 because satisfactory operation of the apparatus is obtained with the stripper fingers 39 vertically disposed whether the vacuum cups 12 move in a vertical or an inclined path.

By this invention, it has been found that the operation of the feeding mechanism can be speeded up to feed several hundred sheets per minute without any damage to the sheets or to the machine being fed.

The invention has been described with particular reference to sheet tinplate but it is to be understood that the invention is well adapted to the feeding of other metal sheets as well as non-metallic sheet materials.

The terms and expressions which I have employed are used as terms of description and not

of limitation, and I have no intention, in the use of such terms and expressions, of excluding any equivalents of the features shown and described or portions thereof, but recognize that various 5 modifications are possible within the scope of the invention claimed.

I claim:

1. Sheet material feeding apparatus comprising a magazine for holding a stack of sheets, vacuum operated gripping means for pulling the lowermost sheet in the stack downwardly at an incline to the vertical, and yieldable stripper fingers having inwardly and downwardly inclined serrated surfaces for engaging the edges of such 10 a sheet and separating it from the sheets thereabove.
2. Apparatus as defined in claim 1 in which the stripper finger surfaces are inclined at substantially the same angle as the angle of movement of the vacuum operated gripping means.

HANS L. KABEL.
